CLAIM

I claim the ornamental design for an artificial intelligence platform device, as shown and described.

DESCRIPTION

FIG. 1 is a perspective view of the artificial intelligence platform device showing my new design.

FIG. 2 is a front view of the artificial intelligence platform device shown in FIG. 1.

FIG. 3 is a back view of the artificial intelligence platform device shown in FIG. 1.

FIG. 4 is a left view of the artificial intelligence platform device shown in FIG. 1.

FIG. 5 is a right view of the artificial intelligence platform device shown in FIG. 1.

FIG. 6 is a top view of the artificial intelligence platform device shown in FIG. 1; and,

FIG. 7 is a bottom view of the artificial intelligence platform device shown in FIG. 1.

The broken lines showing interior features visible through the vent opening around the bottom and the port openings at the bottom rear show portions of the artificial intelligence platform device which form no part of the claimed design.
